Des. 237,814
Patented Nov. 25, 1975

237,814

TREE BASKET OR THE LIKE

William L. Edmonds, Jr., Kenilworth, and Gerald P. Daley, Bensenville, Ill., and Leroy Den Besten, Castleton, N.Y., assignors to T. Equipment Sales Co.

Filed Dec. 13, 1974, Ser. No. 532,717

Term of patent 14 years

Int. Cl. D15—03

U.S. Cl. D35—1

FIG. 1 is a top plan view of a tree basket or the like incorporating our new design;

FIG. 2 is a side view of the tree basket or the like of FIG. 1;

FIG. 3 is a bottom plan view of the tree basket or the like of FIG. 1;

FIG. 4 is a top plan view of a second modified embodiment of the tree basket or the like incorporating our new design;

FIG. 5 is a side view of the tree basket or the like of FIG. 4; and

FIG. 6 is a side view of a third modified embodiment tree basket or the like incorporating our new design.

We claim:

The ornamental design for a tree basket or the like, substantially as shown and described.
